JOURNAL LUBRICATOR

Homer R. Stine, 114 E. 13th St., Newton, Kans.

Filed May 14, 1959, Ser. No. 813,252

5 Claims. (Cl. 308—243)

This invention relates to the lubrication of the journals of railway cars, and more particularly to a novel type of lubricator pad for insertion into a journal box on such cars between the journal surface and the adjacent bottom and side wall portion of the box.

Since the packing of journal boxes with cotton waste previously was responsible for almost 90% of "hot boxes" or bearing failures, cotton waste type lubricators are fast being replaced.

Through years of experience in railroad work, as well as through actual experimentation with various types of journal lubricators, and the testing of such lubricators in actual use, I have concluded that the chief cause of "hot boxes" or bearing failures today is dust entering the journal box and creating what I term "dust glaze," which is an accumulation of dust on at least a portion of that surface of the lubricator pad which periodically contacts the surface of the journal.

During operation of a railroad car at high speeds, high velocity air currents are created in the vicinity of the journal boxes, and dust enters the boxes and settles on all exposed surfaces, including those surfaces of the lubricator pads which are immediately adjacent the journal. As is well known to those familiar with this art a journal may move as much as $\frac{3}{8}$ " to $\frac{1}{2}$ " fore or aft, or up or down, with relation to the walls of the journal box. Such journal movement may be occasioned by severe road impact, by a sudden stoppage of the car, by a reversal in direction of car travel, etc. When direction of travel is reversed, for instance, a journal may move aft in its box $\frac{1}{2}$ ". This means that a portion of the aft lubricator pad which has not previously been in contact with the journal, now comes into actual journal contact. Since the mentioned portion of the lubricator has previously been exposed to settling dust, the dust glazed portion which is now in contact with the journal surface wipes lubricant from the journal, and causes bearing failure or "hot box."

It is a primary object of this invention to provide a lubricator which embodies its own compressible resilient means for continuously maintaining an adequate portion of its surface in lubricating contact with the journal, regardless of the mentioned relative journal movement.

Another primary object is to provide a lubricator which is so shaped and constructed that it will be periodically moved or rotated a slight distance about an axis parallel to and adjacent the journal, such movement being accomplished by the frictional contact between the surface of the rotating journal and the surface of the lubricator. Such rotation is in a direction which brings a fresh and previously unused portion of the lubricator surface into contact with the journal surface—a surface portion which has previously been submerged in oil in the lower part of the journal box. Such lubricator rotation is also in a direction to move a dust glazed portion of the lubricator pad away from the immediately adjacent journal surface so that it cannot come into contact with the journal surface the next time the journal shifts in its box. Such

2

partial rotation of my pad is neither constant nor predictable. Instead it is periodic, erratic and unpredictable, and depends on variables such as temperature changes, air humidity, frost, condensation in the journal box, etc., as well as on the roughness of car handling, frequency of reversal in direction of car travel, etc. Nevertheless, such partial rotation occurs with sufficient frequency and to a sufficient degree to prevent a previously dust glazed portion of the lubricator surface from 5 coming in contact with the journal surface.

10 My invention will be more clearly understood when the following description is read in connection with the accompanying drawings, in which:

Fig. 1 is a longitudinal sectional view showing my lubricator pads installed in operating position in a conventional journal box, the view being taken along the line 1—1 of Fig. 2;

Fig. 2 is a transverse sectional view taken along the line 2—2 of Fig. 1;

Fig. 3 is an enlarged transverse sectional view through my lubricator showing details of construction;

Fig. 4 is a schematic sectional view illustrating the effect of relative journal movement on my lubricator pads, when in operative position; and

Fig. 5 is a perspective view of a preferred form of canvas harness, which constitutes a part of my lubricator.

Referring to the drawings, my lubricator comprises: a wick like, absorbent, flexible and compressible outer cover 10 in the form of an elongated generally cylindrical sleeve, open at both ends; a cellular, resilient compressible inner core 11 of oil resistant or oil impervious rubberlike material extending substantially from end to end of the sleeve 10; and a tough harness 12 (Fig. 5) of canvas or other similar material, substantially encompassing the core 11, and sewed at its opposite ends to the respective ends of sleeve 10 to prevent any material longitudinal movement of the core 11 with respect to the sleeve.

The sleeve or cover 10 may be made from several 40 layers of terry cloth toweling formed into a blanket or thick sheet with two of its opposite edges butted and lapped slightly, and sewed together in a flat seam, as at 13, Fig. 3. Any other material which is tough and wear-resistant and has the other above mentioned characteristics may be used.

The core 11 is preferably extruded or molded from 45 Buna-N rubber, because this material has the characteristic of maintaining its resilience even while immersed in hot oil. Any other suitable material may be used. 50 Several of the rubberlike plastics would serve the purpose. The cells extend from end to end, and are preferably open throughout their lengths. Their cross sectional size and shape is not critical, but near its longitudinal center the core 11 should have an enlarged longitudinally extending cell defined by a continuous thickened wall 14.

The cross sectional shape of this central cell does not 55 have to be circular as shown. The thicker wall of this central cell gives an added and secondary resilience to the core as a whole. The thinner walled cells are laterally compressed and distorted first and to a greater degree, and the central cell wall is compressed to a lesser degree, but because its resistance to a compressive force is greater, it "backs up" or aids the other cells in maintaining the outer sleeve surface in lubricating contact 60 with the journal, as explained below.

65 It will be understood that the over all length of the sleeve, the core and the harness is substantially the same, and that this length is substantially equal to the length of the journal to be lubricated.

The harness 12 (Fig. 5) is prefabricated prior to assembly of the parts and consists of two parallel side straps 15 and 16 and two end straps 17 and 18, assembled in

the relative positions shown, with their respective adjacent ends sewed firmly together, as indicated by the stitch lines 19.

While the end straps 17 and 18 can be used as "pull" straps for removing the assembled lubricator pad from a journal box, I prefer to sew two separate pull straps 20 and 21 to the opposite ends of the harness.

In completing the assembly, core 11 is inserted into the harness with its opposite ends adjacent the harness ends 17 and 18. This assembly is then compressed slightly by hand and inserted endwise into sleeve 10. The previously sewed ends of the harness are next sewed firmly to the marginal portions of the opposite ends of the sleeve, as indicated in Fig. 1 by stitch lines 22.

It is important to note that my assembled lubricator pad, when not under compression is substantially cylindrical in shape, and that it has no exterior seams or other projections which will interfere with its periodical partial rotation about its long axis when it is under substantially diametrical compression in the journal box.

Installation and removal

Before installing my lubricator in a journal box 23, Figs. 1 and 2, it should be submerged in warm oil until sleeve 10 is thoroughly saturated. Either end of the pad is then inserted into the box opening and compressed to ease it into the space between the journal 24 and the adjacent wall 25 of the box. Two such lubricators are so installed in the relative positions shown in Fig. 2, one on each side of the center of the journal box. They extend lengthwise from journal collar 26 to shoulder 27, which is the length of the bearing 28, to be lubricated.

Operation

As will be understood, the journal box is filled with oil to a level below the journal surface, as indicated by the numeral 29. The sleeve material acts as a wick and continuously feeds oil from the bottom of the journal box to the rotating surface of journal 24.

As previously explained, and as illustrated schematically in Fig. 4, the journal will at times move with relation to the walls of the journal box during car operation. When the car is started in the direction indicated by arrow 30 the journal moves aft and assumes the relative position shown in solid lines. This further compresses lubricator 31 and increases journal friction on the surface of that lubricator. The increased friction causes lubricator 31 to rotate several degrees counterclockwise. This brings a small portion of previously unused lubricator surface into contact with the journal surface, and moves a like portion of lubricator surface, which has previously been exposed to dust, away from the journal surface.

Simultaneously the compressive force of the journal on lubricator 32 is reduced, so that lubricator has little tendency to rotate at that time. Its inherent resilience, however, due to core 11, causes it to expand and maintain lubricating contact with the journal surface.

When the car reaches its destination and begins its return trip in the opposite direction, journal 24 may move to the position shown in broken lines in Fig. 4. Friction against the surface of lubricator 32 is increased, and against lubricator 31 reduced. Lubricator 32 is thus rotated several degrees clockwise about its own long axis, with the result previously described.

Thus no part of the lubricator which has been exposed to settling dust in the upper part of the journal box comes into surface contact with the journal, and the greatest cause of present day "hot boxes" is eliminated.

From the above it will be seen that I have provided a lubricator construction which is sufficiently resilient to maintain an adequate lubricating surface area against the journal at all times regardless of journal movement, and a lubricator which is self-rotating and which always ro-

tates in a direction to move dust laden surfaces away from contact with the journal surface.

Having described the invention with sufficient clarity to enable those familiar with this art to construct and use it, I claim:

1. In a journal assembly which includes a journal which extends through an end wall of and into a journal box which has a liquid lubricant well below the journal, elongated self-rotating lubricator means for transversely compressed positioning between the journal surface and a wall of said lubricant well for conducting lubricant from the well onto the journal surface, said lubricator means comprising: at least one elongated generally right cylindrical cellular core of flexible oil resistant material, the cells of said core being disposed longitudinally and being resiliently deformable transversely, one central cell being larger in cross sectional area and having a considerably thicker wall than the surrounding cells; a combination lubricant wick and cover for said core in the form of a thick walled flexible sleeve of absorbent material encasing the core from end to end; and a flexible strap extending across each end of the sleeve and across the respective adjacent ends of said core and secured to the respective sleeve ends, said straps serving both as handles for the entire lubricator and as means to prevent any material longitudinal movement of the core with respect to the sleeve.

2. In a journal assembly which includes a journal which extends through an end wall of and into a journal box which has a liquid lubricant well below the journal, elongated self-rotating lubricator means for transversely compressed positioning between the journal surface and a wall of said lubricant well for conducting lubricant from the well onto the journal surface, said lubricator means comprising: at least one elongated generally cylindrical honeycomb type core of an oil impervious flexible rubber-like material having its cells disposed longitudinally, and having a relatively large relatively thick walled central cell surrounded by smaller thinner walled cells, said thinner walled cells having a primary resilient resistance to deformation by a radially or transversely applied force, and said central cell having a secondary and greater resilient resistance to deformation by such force; and a combination lubricant wick and cover for said core in the form of a generally cylindrical thick walled sleeve of absorbent material encasing said core from end to end, said sleeve having a bumpless protuberance-free outer surface to present minimum interference to slight periodic movement of the entire lubricator about its own long axis as a result of the frictional contact of its sleeve surface with the rotating journal.

3. The lubricator described in claim 2 in which the ends of said sleeve are open, and means secured to the respective ends of the sleeves and extending across the respective ends of the core for preventing any material relative movement between them.

4. The lubricator described in claim 2 and a combination core harness and handle for removing the compressed lubricator from its position between the journal and the lubricant well wall, said harness consisting of a flexible strap of a width less than the diameter of said sleeve, said strap being positioned between the sleeve and the core, and extending along two diametrically opposite sides of the core and across both its ends to thus encompass the core, said strap being secured to the sleeve adjacent both its ends, those portions of the strap which extend across the respective ends of the core serving to prevent relative movement of the core and sleeve, and also serving as handles for moving the lubricator.

5. A lubricator pad comprising a core member of cellular oil resistant flexible material, generally cylindrical in shape and having the cells run longitudinally of the core member from end to end, said core member provided with a central axially disposed cell having thicker walls than the walls of the outlying cells whereby to

impart to said central cell a greater resistance to lateral deformation than is resident in the cell walls in the out-lying sections of the core, said cells being open at opposite ends of the core and said core being enclosed within a substantially cylindrical sleeve of oil absorbent wicking material, and a strap member secured to at least one end of the sleeve member at substantially diametrically opposite points for confining the core within the

5 sleeve and providing handle means for withdrawing the core and sleeve as a unit from a railway car journal box.
